UNITED STATES PATENT OFFICE

JOSEPH B. ROCHELLE, OF NEW ORLEANS, LOUISIANA, ASSIGNOR TO BOROTHI REFRIGERATING MACHINE CO., INC., OF NEW ORLEANS, LOUISIANA

ICE MAKING APPARATUS

Application filed July 11, 1930. Serial No. 467,307.

The device forming the subject matter of the application is a freezing apparatus or ice-making machine, and one object of the invention is to provide novel means whereby the 5 brine is forced, by the action of a pump, to the bottom of the drop pipe in the ice can, the brine leaving at the top of the drop pipe. The invention aims to provide novel means for securing a circulation of the brine, and 10 to provide novel means for mounting the drop pipe and attendant parts on the ice can.

It is within the province of the disclosure to improve generally and to enhance the utility of devices of that type to which the present 15 invention appertains.

With the above and other objects in view, which will appear as the description proceeds, the invention resides in the combination and arrangement of parts and in the details of 20 of construction hereinafter described and claimed, it being understood that changes may be made in the precise embodiment of the invention herein disclosed, within the scope of what is claimed, without departing 25 from the spirit of the invention.

In the accompanying drawings:

Figure 1 shows in horizontal section, a device constructed in accordance with the invention, most parts appearing in top plan, 30 and the cover for the tank having been removed;

Figure 2 is a vertical section;

Figure 3 is a top plan of one of the ice cans;

Figure 4 is a section of the ice can;

Figure 5 is a vertical section of the ice can and parts within it;

Figure 6 is an elevation of the ventilating mechanism for the brine tank.

The numeral 1 marks a brine tank including a cover 2, part of which is removable. Referring to Figure 6 of the drawings, the brine tank 1 is ventilated through a stack 3 on the cover 2, the fumes passing from the tank into the stack 3 through a pipe 4 in 45 which a valve 5 is interposed.

A hollow pedestal 6 is mounted on the cover 2 of the brine tank 1, and a vertical vent pipe 7 communicates with the pedestal

6. A lateral pipe 8 communicates with the pedestal 6. The inner end of the lateral pipe

8 is upwardly inclined and terminates in a substantially vertical nozzle 9 located within the stack 3. The numeral 10 marks a horizontal air inlet which is mounted at 11 on the upper end of the vent pipe 7, to swing horizontally. A vane 12 is secured to the funnel 10 and keeps the funnel headed into the wind. Air moves through the funnel 10, through the pipe 7, through the pipe 8, and through the nozzle 9, air being discharged 55 into the stack 3, to aid in carrying the fumes out of the brine tank 1, through the pipe 4 and the stack 3.

An inlet header 14 extends crosswise of the brine tank 1, at one end thereof. A U-shaped pipe 15, shown in Figure 1, connects one end of the header 14 with the brine tank 1. In the pipe 15, a combined suction and force pump 16 is interposed.

That end of the inlet header 14 which is 70 remote from the pipe 15 is connected to a water inlet pipe 17 provided with a valve 18 under the control of an operator. The water inlet pipe 17 is used for washing out the brine line, when the valve 18 is opened, also 75 by circulating steam from the pipe 17 through the brine line the drop line may be thawed out facilitating removal of the center line.

An air inlet pipe 19 is connected to the 80 header 14, a valve 20 under the control of an operator, being interposed in the air inlet pipe 19. The air inlet pipe 19 is used, when the valve 20 is opened, for blowing out the brine from the brine line back into the tank 1. 85

An outlet header 21 extends across the brine tank 1, at that end of the brine tank which is remote from the inlet header 14. The outlet header 21 is connected at one end, by a U-shaped pipe 22, to the brine tank 1. 90 The U-shaped return pipe 22 carries a valve 23, under the control of an operator. The numeral 24 designates an outlet, connected to the pipe 22, a valve 25, under the control of an operator, being interposed in the pipe 24. The valve 25 is opened in order to enable the brine system to be washed out through the pipe 24.

A first pipe 26 is joined at one end to the inlet header 14 and is disposed adjacent to 100

one end of the tank. The pipe 26 is closed at its end, adjacent to the header 21, as shown in Figure 1. In the pipe 26 there is a valve 35 under the control of an operator, and disposed adjacent to the header 14.

Another first pipe 28 extends along that side of the brine tank 1 which is remote from the pipe 26. The pipe 28 is in communication with the outlet header 21. The pipe 28 is closed at 29, adjacent to the inlet header 14. A valve 32, under the control of an operator, is interposed in the pipe 28 and is disposed near to the outlet header 21.

A second pipe 30 is disposed between the pipes 28 and 26 and is joined at one end to the outlet manifold 21. The opposite end of the pipe 30 is closed, as shown at 31. There is a valve 34 in the pipe 30, near to the outlet manifold 21. Underneath the pipe 34 is located another second pipe 60. The pipe 60 is connected at one end to the inlet header 14. The opposite end of the pipe 60 is closed as shown at 59. A valve 58, under the control of an operator, is interposed in the pipe 60 and is disposed adjacent to the inlet header or manifold 14, as shown in Figure 2.

Referring to Figure 1, the machine is shown as containing two lines of ice cans 36, although there may be any number of these ice cans. Moreover, the ice cans 36 may be of any desired shape and size.

Referring especially to Figures 4 and 3, it will be seen that brackets 37 are mounted removably on the upper edges of the ice cans 36. At their ends, the brackets 37 have suspension elements 38, engaging the ice cans 36 to support the brackets 37, and to prevent the brackets 37 from moving endwise.

Drop pipes 39 are mounted in the brackets 37, as shown at 40, by means of clamp nuts. The drop pipes 39 may be of any desired shape, and there may be as many or as few of them, to each ice can 36, as the operator wishes. The drop pipes 39 are closed at the bottom, as shown at 41. Each drop pipe 39 has a top 42. Tubes 43 extend downwardly through the tops 42 of the drop pipes 39, and terminate a short distance from the bottoms of the drop pipes, as shown in Figure 5.

Referring especially to Figure 1, it will be seen that pipes 44, which may be pieces of flexible hose, are detachably connected at 45 to the upper ends of the tubes 43. Pipes 46, which may be lengths of flexible hose, are detachably connected to the pipe tops 42 of the drop pipes 39, and communicate with the drop pipes, near to the upper ends of the drop pipes. The pipes 46 are detachably connected, or joined otherwise, to the pipe 30 which 60 communicates with the outlet header 21. The foregoing description as to the pipes 44 and 46, relates especially to the lowermost of ice cans 36 in Figure 1.

As to the uppermost line of ice cans 36 in 65 this figure, these cans derive their supply of

brine from the pipe 60 that is joined to the inlet header 14, the brine entering the drop pipe through the pipes 48, which correspond to the pipes 44, the brine leaving the drop pipes through the pipes 49, which correspond to the pipes 46, the pipes 49 communicating with the pipe 28, which, in turn, communicates with the outlet header 21.

The brine is drawn by the pump 16 of Figure 1 from the tank 1 and is forced 75 through the pipe 15 into the inlet header 14. From the inlet header 14, the brine moves into the pipe 26 and thence through the pipes 44 into the tubes 43 of Figure 5, the brine being discharged downwardly on the bottoms 80 of the drop pipes 39. The brine moves upwardly in the drop pipes 39 and finds an exit through the pipes 46, the pipe 30, and the outlet header 21.

As to the uppermost line of ice cans 36 in 85 Figure 1, the brine comes from the header 14 and moves along the pipe 60, the brine passing into the drop pipes 39 through the pipes 48 and finding an exit by way of the pipes 49 and the pipes 28, into the header 21. 90

Referring to Figure 5, in connection with Figure 6, it will be obvious that the pump 16 will force the brine downwardly through the tube 43 upon the bottom 41 of the drop pipe 39, the brine filling the drop pipe and passing 95 out of the top of the drop pipe. An unusually efficient operation results. Much time is saved in the operation of the machine. The structure may be used either for making ice or for freezing fruit, fish, and the like. 100

Having thus described the invention, what is claimed is:

1. In an ice-making machine, a tank, rows of ice cans in the tank, an inlet header extended transversely of the rows of cans and located at one end of the tank, an outlet header extended transversely of the rows of cans and located at the opposite end of the tank in substantially parallel relation to the inlet header, first pipes located at the outer sides of the rows of cans, each of the first pipes being closed at one end, the opposite ends of the first pipes being connected, respectively, to the inlet header and to the outlet header, the first pipes being arranged substantially at right angles to the headers, second pipes located at the inner sides of the rows of cans in substantially parallel relation to the first pipes, each of the second pipes being closed at one end, the opposite ends of the second pipes being connected, respectively, to the inlet header and to the outlet header, drop pipes in the ice cans, tubes in the drop pipes, connections between the first pipe that communicates with the outlet header, and the drop pipes of one row, and connections between the tubes of said one row and the second pipe that communicates with the inlet header, connections between the second pipe that communicates

with the outlet header, and the drop pipes of the other row, and connections between the tubes of said other row and the second pipe that communicates with the inlet header, all 5 of said connections being short, detachable, and located entirely at the tops of the cans.

2. In an ice making machine, an ice can, a bracket removably mounted on the ice can, a drop pipe extended through the bracket 10 and having a closed top located above the bracket, clamps on the drop pipe and engaging the upper and lower surfaces of the bracket, a tube extending down into the drop pipe, through the said top of the drop 15 pipe and independently of the bracket, and an outlet member for the drop pipe, the outlet member being mounted in said top of the drop pipe, independently of the bracket.

In testimony that I claim the foregoing as 20 my own, I have hereto affixed my signature.

JOSEPH B. ROCHELLE.
